UNITED STATES PATENT OFFICE.

UGO MALVISI, OF TURIN, ITALY.

SPRING-GRIP DUMB-BELL AND EXERCISER.

1,130,620.

Specification of Letters Patent.

Patented Mar. 2, 1915.

Application filed May 13, 1912. Serial No. 697,017.

To all whom it may concern:

Be it known that I, UGO MALVISI, manufacturer, a subject of the King of Italy, residing at 10 Via Burdin, Turin, Italy, 5 have invented certain new and useful Improvements in Spring-Grip Dumb-Bells and Exercisers; and I do hereby declare the following to be a full, clear, and exact description of the invention, such as will enable 10 others skilled in the art to which is appertains to make and use the same, reference being had to the accompanying drawings, and to letters or figures of reference marked thereon, which form a part of this specification.

This invention relates to dumb-bells of the spring grip type, and has for object improved dumb-bells of this type in which the springs may be much smaller than those 20 of present spring grip dumb-bells while offering a wider range of resistances to pressing together the halves of the dumb-bell.

The invention consists in an improved spring grip dumb-bell the main feature of 25 which is that the springs are of the volute type and preferably biconical.

An embodiment of the invention is illustrated by way of example in the accompanying drawing, showing a dumb-bell in longitudinal section.

In accordance with the invention the springs 1 are of volute and biconical form, made in known manner from a strip of steel of suitable shape coiled in a helix. These 35 springs are arranged transversely and in any suitable number between the two halves 2, 3 of the dumb-bell and accommodated in easily exchangeable manner in the desired position by means of pins 4 arranged in 40 opposite pairs projecting from the inner faces of the dumb-bell halves, the ends of the volute springs fitting over these pins. This method of mounting the springs 1 has the advantage of allowing the springs to be 45 easily removed or interchanged for the purpose of varying the resistance to the grip of the dumb-bell, but any other suitable method of mounting the springs may be adopted.

50 In the embodiment of the invention illustrated in the figure, the two dumb-bell halves are of C-shape and arranged capable

of sliding one in the other along their lateral arms by means of slots 5 in the arms of one of the halves in which engage pins 7 55 fixed to the ends of the arms of the other half, the length of the said slots being such as to suitably limit the maximum separation and approach of the halves. The halves are provided with external facings 2' 3' of 60 wood or other material attached by suitable screws 2" 3".

In the foregoing description and in the embodiment of the invention illustrated in the drawing, biconical volute springs have 65 been assumed, these being preferable in this kind of application. It should be observed however that simple conical volute springs may be used.

Having now particularly described and 70 ascertained the nature of my said invention and in what manner the same is to be performed, I declare that what I claim is:—

1. A spring grip dumb-bell, having a right hand and a left hand shell, said shells 75 interengaging with each other and being provided with a plurality of oppositely situated pins, a plurality of volute springs between said shells held in position by said pins.

2. A spring grip dumb-bell, having a right hand and a left hand shell, said shells 80 interengaging with each other and being provided with a plurality of oppositely situated pins, a plurality of volute springs between said shells held in position by said pins, said springs being of bi-conical shape 85 with their smaller ends engaging said pins.

3. A spring grip dumb-bell, having a right hand and a left hand shell, said shells 90 interengaging with each other and being provided with a plurality of oppositely situated pins, a plurality of volute springs between said shells held in position by said pins, said springs being of bi-conical shape 95 with their smaller ends engaging said pins, an external cover for each shell shaped to provide a comfortable grip.

The foregoing specification signed at Turin (Italy) this 2nd day of May, 1912.

UGO MALVISI.

In presence of two witnesses:

PIERO GIANOLIO,
JOCELYN SOUBEYRAN.
